[57] **CLAIM**

The ornamental design for a portable pipe end preparation tool with right angle feed control, as shown.

DESCRIPTION

FIG. 1 is a side elevational view of a pipe end preparation tool with right angle feed control showing my new design;

FIG. 2 is a bottom plan view thereof;

FIG. 3 is a side elevational view of the side opposite that shown in FIG. 1;

FIG. 4 is a top plan view thereof;

FIG. 5 is a front elevational view taken from the right of FIG. 1;

FIG. 6 is a rear elevational view taken from the left of FIG. 1.

FIG. 2

FIG. 1

FIG 3

FIG 4

FIG 5

FIG 6
